UNITED STATES PATENT OFFICE.

LUDWIG B. GLANTZ, OF MINDEN, NEBRASKA.

SHARPENING ATTACHMENT FOR ENSILAGE-CUTTERS.

1,149,255.

Specification of Letters Patent. Patented Aug. 10, 1915.

Application filed March 10, 1914. Serial No. 823,821.

To all whom it may concern:

Be it known that I, LUDWIG B. GLANTZ, a citizen of the United States, residing at Minden, in the county of Kearney and State of Nebraska, have invented certain new and useful Improvements in Sharpening Attachments for Ensilage-Cutters, of which the following is a specification.

This invention relates to an attachment which is removably connected with an ensilage cutter, and which is intended to be used for sharpening the cutting knives of the ensilage cutter.

One of the principal objects of the invention is to provide a sharpener which may be removably connected with the frame of the ensilage cutter and which can be easily and quickly put in place and removed.

Another important object of the invention is to provide a sharpener which is so constructed that it may be driven from the belt which passes around the pulley wheel mounted upon the driven shaft with which the cutting knives are connected.

Another object of the invention is to so construct the frame of the sharpener that the driving wheel of the sharpener may be moved out of engagement with the driving belt of the ensilage machine.

Another object of the invention is to so mount the carriage which is supported by the frame of the sharpener that the grinding wheel may follow the curvature of the cutting knives when moved longitudinally of the cutting blades.

Another object of the invention is to so construct the sharpener that it will be comparatively simple in construction and so formed that it will not be cumbersome and unwieldy to handle thus permitting the sharpener to be easily connected with the machine or removed from the machine.

This invention is illustrated in the accompanying drawings wherein—

Figure 1 is a sectional view taken along the line A—A of Fig. 2 showing the principal portion of the construction disclosed in side elevation; Fig. 2 is a section taken along the line 2—2 of Fig. 1 and showing the principal portion of the machine and sharpener disclosed in front elevation; Fig. 3 is a section taken along the line 3—3 of Fig. 2; Fig. 4 is a transverse section taken along the line 4—4 of Fig. 3; Fig. 5 is a perspective view of a yoke which is knotted upon the pivot bolt shown in Fig. 4. Fig.

6 is a fragmentary view in elevation of the right-hand portion of Fig. 2 and looking in the opposite direction; Fig. 7 is a view taken along the line 7—7 of Fig. 6.

The feeding roller 10' has its shaft 11 rotatably mounted in bearings carried by the frame 10 of the ensilage cutter and extends beyond one side of the frame so that the large gear wheels 12 may be rigidly mounted upon the shaft 11. This large gear-wheel 12 meshes with the small gear wheel 13 mounted upon the driven shaft 14 and it will thus be seen that when the driven shaft 14 is rotated by the belt 15, which passes around the rigidly mounted pulley wheel 16, rotary motion will be transmitted by the gears 13 and 12 to the shaft 11 which carries the roller 10'. Hubs are rigidly mounted upon the driven shaft 14 and carries spokes 18 with which the cutting blades 19 are connected. The cutting knives of this machine are somewhat similar to the cutting knives of a lawn mower and when in operation are intended to cut the ensilage which is fed by the feed roller 10' into small pieces which will pass out of the ensilage cutting machine through the spout 20.

A bracket or bar 21 is slidably mounted upon a bolt 22 carried by the frame 10. This bolt 22 passes through a slot 23 formed in the bracket 21 and carries a winged nut 24 which engages the bracket 21 and thus releasably holds the bracket in a desired position. A shaft 25 is rotatably mounted in the bearings 26 at the upper ends of the forks 27 and 28 of the bracket 21 and extends beyond the bearing of fork 28 so that the pulley wheel 29 may be rigidly mounted upon the shaft 25. A gear wheel 30 is rigidly mounted upon the shaft 25 so that when the shaft 25 is rotated, rotary motion may be transmitted through the gear wheels 30 and 31 to the shaft 32 upon which the gear wheel 31 is rigidly mounted.

A guiding strip or track 33 extends transversely across the frame 10 and has one end secured to the standard 34 which is secured to one of the bearings 35 of shaft 14 by means of the bolt 36. This strip or track 33 extends parallel to the cutting edges of the blades 19 and has its opposite end portion secured to the upper end of the strip 37 which has its lower end provided with the bearing clamp 38. This bearing clamp 38 is secured about the shaft 14 and it will thus be seen that the strip 37 can

be connected with the shaft 14 without the rotation of the shaft 14 being interfered with. In order to support the shaft 32 there has been provided arms 39 which are secured to the strip 33 and have their upper ends formed into bearings 40 through which the shaft 32 passes. Hanger brackets 41 are pivotally mounted upon the shaft 32 and have their lower ends connected by a bearing 42 through which the shaft 25 passes. It will thus be seen that by adjusting the bracket 21, the shaft 25 may be swung upwardly and downwardly and thus move the pulley 29 into and out of engagement with the drive belt 15. By this construction the ensilage cutter can be operated without the sharpening device being operated and therefore it is not necessary to remove the sharpening attachment when the ensilage cutter is in use unless it is desired to transfer the attachment from one machine to another or for the purpose of making repairs to the sharpening attachment.

25 A carriage 43 is slidably mounted upon the track 33 and is intended to be moved transversely across the ensilage cutter so that the grinding stone may be moved longitudinally along the cutting edges of the blades 19. A bushing 44 is placed in the carriage 43 to take up wear caused by frictional engagement with the track 33. A bearing 45 through which the shaft 46 passes is provided with hinge ears 47 which are pivotally connected with the hinge ear 48 of carriage 43 by means of a pivot pin 49. A yoke 50 is placed upon the pin 47 with its arms 51 engaging the upper and lower edges of one of the hinge ears 47. 40 From the lower end portion of the yoke 50 there extends an arm 52 which has its end portion bent to form a finger 53 with which a rod 54 is pivotally connected. It will thus be seen that by means of the rod 54, the bearing through which the shaft 46 passes may be pivotally moved with respect to the carriage 43 thus bringing the grinding stone 55 into and out of engagement with the cutting blades 19. A collar 56 is placed upon the shaft 46 between the bearing 45 and bevel gear 57 and is provided with a liner sleeve 58 which extends into the bushing 59 placed in the bearing 45. From the collar 56 there extends the yoke arms 60 which have their upper ends formed into bearings 61 slidably mounted upon the shaft 62. This shaft 62 which is connected with the shaft 32 by means of a universal joint 63 is provided with a longitudinally-extending groove 64 so that the bevel gear 65 may be keyed to the shaft 62 and thus permitted to slide upon the shaft 64 but at the same time caused to rotate with the shaft 62.

65 The operation of this attachment is as follows: The frame of the attachment is

connected with the frame of the ensilage cutter by securing the bearing clamp 38 about the shaft 14 and then connecting the standard 34 with the bearing 35. After the frame of the sharpening attachment is in place the arm or bracket 21 is placed in engagement with the bolt 22 and the arm 21 either raised to move the pulley 29 out of engagement with the belt 15 or lowered so that the belt will engage the pulley. The wing nut 24 will, of course, be tightened so as to hold the bracket 21 in the adjusted position. When this device is being operated, the pulley 16 will be released from the shaft 14 so that the shaft will be rotated and the cutting knives will thus be prevented from rotating when it is desired to sharpen the same. When the pulley wheel 29 is in engagement with the belt 15, rotary motion will be transmitted through the relatively large and small gear wheels 30 and 31 to the shaft 32 and transmitted from the shaft 32 to the shaft 64. The relatively large bevel gear 65 will transmit rotary motion through the relatively small bevel gear 57 to the shaft 46 which carries the grinding stone 55 and it will thus be seen that the grinding stone 55 will be very rapidly rotated. The cutting blades 19 are successively brought into the position shown in Fig. 1 so that the grinding stone can engage the cutting edges of the blades and the carriage is then moved along the track 33 to cause the grinding stone to travel from one end of the cutting blades to the other. The carriage is moved by means of the rod 54 which may also be used for rocking the bearing 45 upon the pivot pin 49 thus causing the grinding stone to bear against the cutting edge of the blade with as much pressure as desired.

After the blades of the knife have been sharpened, the carriage may be moved to the right hand end of the track so that the grinding stone will not be liable to strike the blades of the revolving knife. The frame or bracket 21 can now be raised and held in the raised position by the clamping nut 22 and the pulley wheel 29 will be out of engagement with the belt 15. The pulley wheel 16 is now again securely connected with the shaft 14 and the ensilage cutter is ready for operation. This attachment may be left upon the machine while using the same and can be removed and put away for safe keeping when the ensilage cutter is no longer needed. This attachment should be left upon the machine while using the same since the knives of the ensilage cutter require sharpening at least twice a day in order to keep them in good condition and therefore it would not be convenient to connect the sharpening attachment with the machine every time the knives needed sharpening. It should also be noted that with this attachment it is not

necessary to remove the cutting knives from the ensilage cutting machine and therefore the knives do not have to be adjusted after being sharpened.

5 What is claimed is:

1. In an ensilage cutting machine, a frame including a track, a carriage movably mounted upon said track and including a pivotally mounted bearing, a shaft rotatably mounted in said bearing, a grinding element carried by said shaft, means for pivotally moving said bearing whereby said grinding element may be moved into and out of operative position, a driven shaft carried by said frame, means for transmitting rotary motion from said driven shaft to said last mentioned shaft, a bearing provided with hanger brackets carried by said driven shaft, a driving shaft mounted in said last mentioned bearing, a bracket having its upper end portion formed into forked arms for engaging said driving shaft whereby said driving shaft may be moved to travel about said driven shaft and adjust the position of said driving shaft, and means for transmitting rotary motion from said driving shaft to said driven shaft.
2. An attachment for an ensilage cutting machine comprising a supporting frame including a track, a driven shaft rotatably carried by said supporting frame, a carriage movably mounted upon said track including a pivotally mounted bearing, a pivot pin for pivotally mounting said bearing, a yoke rotatably mounted upon said pivot pin and provided with fingers engaging said bearing, an arm extending from said yoke and having its free end portion formed into a finger, means connected with said last-mentioned finger for moving said yoke to pivotally move said bearing, a shaft rotatably mounted in said bearing, a grinding element carried by said shaft, means for transmitting rotary motion from said driven shaft to said last-mentioned shaft, and means for transmitting rotary motion to said driven shaft.
3. An attachment for an ensilage cutting machine comprising a frame, a carriage movably mounted upon said frame, a bearing pivotally connected with said carriage, a driven shaft carried by said frame, a shaft

rotatably mounted in said bearing, a collar mounted upon said shaft and provided with arms having their free ends formed into 55 bearings slidably mounted upon said driven shaft, means for transmitting rotary motion from said driven shaft to said last-mentioned shaft, means for moving said carriage from one side of said frame to the other, 60 and means for transmitting rotary motion to said driven shaft.

4. An attachment for an ensilage cutting machine comprising a frame, a driven shaft carried by said frame, a carriage movably 65 mounted upon said frame and including a bearing, a pivotally mounted shaft rotatably mounted in said bearing, a grinding element carried by said shaft, a collar loosely mounted upon said shaft and provided with arms 70 having their upper ends slidably connected with said driven shaft, means for transmitting rotary motion from said driven shaft to said last-mentioned shaft, and means for transmitting rotary motion to said driven 75 shaft.

5. In an ensilage cutting machine a frame including a track, a carriage movably mounted upon said track and including a pivotally mounted bearing, a shaft rotatably mounted 80 in said bearing, a grinding element carried by said shaft, means for pivotally moving said bearing whereby said grinding element may be moved into and out of operative position, a driven shaft carried by said frame, 85 means for transmitting rotary motion from said driven shaft to said last mentioned shaft, and means for rotating said driven shaft.

6. In an ensilage cutting machine a frame 90 including a track, a carriage movably mounted upon said track, a bearing, means for pivotally connecting said bearing with said carriage, a shaft rotatably mounted in said bearing, an operating element carried by 95 said shaft, and means for rotating said shaft.

In testimony whereof I affix my signature in presence of two witnesses.

LUDWIG B. GLANTZ.
